UNITED STATES PATENT OFFICE

152,926

DESIGN FOR A BOTTLE OR SIMILAR ARTICLE

James S. Steelman, Millville, N. J., assignor to Armstrong Cork Company, Lancaster, Pa., a corporation of Pennsylvania

Application January 29, 1946, Serial No. 126,063

Term of patent 14 years

(Cl. D58—8)

To all whom it may concern:

Be it known that I, James S. Steelman, a citizen of the United States, residing in Millville, county of Cumberland, and State of New Jersey, have invented a new, original, and ornamental Design for a Bottle or Similar Article, of which the following is a specification, reference being had to the accompanying drawing, forming a part thereof, and in which

The dominant features of my design reside in the portion shown in solid lines.

I claim:

The ornamental design for a bottle or similar article, substantially as shown and described.

JAMES S. STEELMAN.
